UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A BOTTLE OR SIMILAR ARTICLE.

Application filed February 16, 1920. Serial No. 359,190. Term of patent 14 years.

To all whom it may concern:

Be it known that I, ANDREW J. SANFORD, a citizen of the United States, residing at Newark, Ohio, have invented a new, original, and ornamental Design for a Bottle or Similar Article, of which the following is a specification.

The drawing is a side elevation of cologne bottle embodying the invention. The transparency of the article cannot be well delineated by black and white line drawing, nor can the hollow interior thereof be well illustrated for the same reason. The ornamentation involved in the design resides in the outline or contour, and appearance of the article.

I claim:—

The ornamental design for a bottle or similar article substantially as shown and described.

ANDREW J. SANFORD.
